United States Patent Office

Des. 185,995

Patented Aug. 25, 1959

185,995

CAMERA

Arthur H. Crapsey, Jr., Rochester, N.Y., assignor to Eastman Kodak Company, Rochester, N.Y., a corporation of New Jersey

Application March 23, 1959, Serial No. 55,112

Term of patent 7 years

(Cl. D61—1)

Fig. 1

Fig. 2

Fig. 3

Fig. 4

Fig. 5

Fig. 1 is a front perspective view of a camera, showing my new design;

Fig. 2 is a top plan view thereof;

Fig. 3 is a rear perspective view thereof;

Fig. 4 is a bottom plan view thereof; and

Fig. 5 is a fragmentary vertical sectional view, taken substantially on line 5—5 of Fig. 2, and showing the contour of the top wall thereof.

Portions of the drawing figures are provided with light diagonal shade lines to indicate that these parts are transparent.

I claim:

The ornamental design for a camera, as shown and described.
